US00D598613S

(12) **United States Design Patent**
Walston et al.

(10) **Patent No.:** US D598,613 S
(45) **Date of Patent:** ** Aug. 18, 2009

(54) **PET FOOT APPAREL**

(76) Inventors: **Lorraine J. Walston**, 702 Iris Gardens Ct., San Jose, CA (US) 95125; **James Valenti**, P.O. Box 1560, Cottage Grove, OR (US) 97424

(**) Term: **14 Years**

(21) Appl. No.: **29/288,525**

(22) Filed: **Jun. 14, 2007**

(51) **LOC (9) Cl.** 30-01

(52) **U.S. Cl.** D30/146

(58) **Field of Classification Search** D30/145,

(57) **CLAIM**

The ornamental design for a pet foot apparel, as shown and described.

DESCRIPTION

FIG. 1 is a left side view of one embodiment of the pet foot apparel showing a new design;

FIG. 2 is a right side view of the embodiment shown in FIG. 1; and,

FIG. 3 is a bottom view of the embodiment shown in FIG. 1. All components of the appended drawings which are shown in broken lines are for illustrative purposes only and form no part of the claimed invention for the specified embodiment. The paw print design appears substantially flat.
